ATTORNEY

UNITED STATES PATENT OFFICE.

CHARLES F. MOSMAN, OF BRIDGEPORT, CONNECTICUT, ASSIGNOR TO
ANDREW KROUSE, OF SAME PLACE.

DESIGN FOR A PICTURE-FRAME.

SPECIFICATION forming part of Design No. 23,388, dated June 19, 1894.

Application filed May 23, 1894. Serial No. 512,236. Term of patent 3½ years.

To all whom it may concern:

Be it known that I, CHARLES F. MOSMAN, a citizen of the United States, residing at Bridgeport, in the county of Fairfield and State of Connecticut, have invented and produced a new and original Design for Frames for Pictures, of which the following is a specification, reference being had to the accompanying illustration, which fully represents the nature and features of my design.

The leading features of my design consist of the representation of a balcony window with a scroll like lattice work at the bottom, a figure representing a Romeo kneeling at one side of the balcony in a corner of the frame, a combined floral and foliate pattern upon the frame and surrounding the opening therein.

1 is the opening in the frame which represents the window, 2 the scroll like lattice work at the bottom of the window, 3 the figure of the Romeo, and 4 the combined floral and foliate pattern which surrounds the window and covers the face of the frame.

I claim—

The design for a picture frame substantially as shown in the accompanying drawing.

In testimony whereof I affix my signature in presence of two witnesses.

CHARLES F. MOSMAN.
